MEANS FOR ABSORBING ICE PRESSURE

John Franz Feek, Norwood, Ohio

Application February 19, 1948, Serial No. 9,398

3 Claims. (Cl. 119—77)

1

This invention relates to improvements in means for absorbing ice pressure and particularly for preventing the cracking, distorting or breaking of containers having water or liquid therein when in, or exposed to, freezing temperatures.

The invention is illustrated in the drawings and will be described in connection with its use in fowl drinking fountains, for example, in fowl drinking fountains operating on the barometric principle. In the past fowl drinking fountains operating on the barometric principle have been made and used in which water containers of glass, metal and the like are employed and which containers are adapted to be broken or distorted by the pressure of ice formed from the water therein.

The principal object of the present invention is, therefore, the provision of means for absorbing the pressure of ice while forming in containers or receptacles whether said containers or receptacles are subject to freezing temperatures in nature or in an atmosphere artificially or mechanically produced or created.

Another object of the present invention is the provision of a fowl drinking fountain wherein use is made of a container capable of being distorted or broken and having associated therewith means whereby if ice forms in the container the walls thereof will not crack, distort, or break.

Another object of the present invention is the provision of the fowl drinking fountain that has a base in combination with a container, and wherein said base may be formed and said container has associated therewith means of flexible material whereby ice that forms therein will not distort or break either the base or container.

A further and specific object of the present invention is the provision of a device that may be used as an attachment to fowl drinking fountains as heretofore used and employed to safeguard the containers thereof against distortion and breakage by the expanding pressure of ice forming therein.

A specific object of the present invention is the provision of a compressible device adapted to be placed in the water of fowl drinking fountains to absorb the pressure resulting from ice formation within the fountain container.

A still further object of the present invention is the provision of a fowl drinking fountain for accomplishing the foregoing objects that is extremely simple in construction and economical to produce.

2

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a front elevational view of a fowl drinking fountain embodying the principles of the present invention.

Fig. 2 is a top plan view of the fowl drinking fountain of Fig. 1.

Fig. 3 is a vertical cross-sectional view of the fowl drinking fountain as seen on line 3—3 on said Fig. 2.

Fig. 4 is a horizontal cross-sectional view of the fowl drinking fountain as seen on line 4—4 on said Fig. 3.

Fig. 5 is a vertical cross-sectional view of the fowl drinking fountain taken in the same plane as Fig. 3 and showing a modification in the construction thereof.

Fig. 6 is a vertical cross-sectional view of the fowl drinking fountain similar to Fig. 5 only showing a nonflexible material for the base member.

Fig. 7 is a vertical cross-sectional view taken centrally of an expansion or compression member showing a further modification in construction thereof.

Fig. 8 is a vertical cross-sectional view of a container having associated therewith the expansion or compression member of the present invention and illustrating a modification in the invention.

Throughout the several views of the drawings similar reference characters are employed to denote the same or similar parts.

Fowl drinking fountains operating on the barometric principle are old but those heretofore have made no provision for the freezing of the water in the container. Upon the freezing of said water and expansion of the resulting ice it is often found that the walls of the container member would crack, distort or break. The fowl drinking fountain of the present invention has eliminated all such inherent drawbacks, as will presently be made clear.

The fowl drinking fountain of the present invention consists of an upper portion or container 10 and a lower portion or base 11. The container 10 is of a construction similar to any common

jar having the body portion of a cylindrical shape as at 12 terminating at one end in a bottom 13. The jar body portion at its other end terminates in a reduced portion or neck 14 of a diameter somewhat smaller than the diameter of the body portion 12. Beyond the neck 14 the container is slightly enlarged as at 15 and has formed on the outer surface thereof threads 16 for attachment to the drinking fountain base 11 as is well known. It should be noted that other means may be employed instead of the threads 16 for attaching these parts.

The container 10 is shown in Figs. 3, 5 and 6 as constructed of glass but it is to be understood that said container may also be constructed from metal, crockery or any other material.

The base 11 of the fowl drinking fountain is provided with a flat body portion 17 the outer edges of which upstands to form a rim as at 18. As shown in the drawings the rim 18 is downturned as at 19 to form a flange, the lower edge of which, along with the body portion 17, forms the supporting surface for the fountain. Substantially centrally of the base body portion is an upstanding hollow boss 20 internally threaded to receive the external threads 16 of the container. The outer surface of the central boss 20 and the opposed inner surface of the rim 18 form between them a trough 21 into which the water flows from the container 10 through a discharge opening or hole 22 in the boss wall.

Substantially centrally of the hollow boss 20, the base body portion 11 has rising therefrom a compression member in the form of a stem or post 23 centrally cored as at 24 to a point just short of the upper end thereof. The base 11 including the stem or post 23 is preferably formed of deformable or compressible material, such as rubber for a purpose subsequently to be made clear.

The user upon desiring to use the fowl drinking fountain positions the fountain reversely from that shown in Fig. 3, namely, on the bottom 13 of the jar having previously unscrewed or then unscrews the base 11 from the container 10 and fills the jar with the desired amount of water. The user then connects the jar and base by screwing the base 11 home on container 10 with the stem or post 23 in said water and then positions the assembled fountain to its original position, as shown in Figs. 1 and 3.

The positioning of the fowl drinking fountain to its original position causes the water to flow through the hole or discharge opening 22, which is located substantially at a point just below the end jar threads 16 in the hollow boss 20, into the trough 21. The water will rise in the trough 21 until it reaches a point where it seals off the hole or discharge opening 22, whereupon the water will remain at that level, being automatically replenished from the jar reservoir. This operation is in accordance with the well known barometric principle.

If the water 25 in the container 10 were to freeze it would expand as it became ice. This expansion, it has been found, would be absorbed by the stem or post compression member 23 thus preventing the walls or sides of the container 10 from cracking, distorting or breaking as would be the case if the compression member 23 were not present, and the water in the base 11 upon freezing and expanding would only flex the material from which the said base is formed.

The user upon finding the water 25 frozen in the base 11, which is formed of a flexible mate-

rial, such as rubber, only has to peel the base member back from the ice, and remove the said ice in a manner similar to that in removing the ice cubes from an ice forming tray in a mechanical refrigerator. The stem or post 23 is readily removed from the ice in the container 10 upon slight manipulation thereby leaving a hole in the ice whereby the said ice in the container is easily removed therefrom. By this construction the container is not only prevented from destruction but is readily returned to use again.

The modification of the invention shown in Fig. 5 is very similar to that shown in Fig. 3 except that the compression member, stem or post 26, is formed separately from the base instead of integral therewith. In this modification the base member 11' consists of a body portion 17', a hollow upstanding boss 20, a flange or rim 18 and a trough 21. The body member 17' has centrally of the hollow boss 20 a substantially smooth flat surface 27 upon which is placed a removable compression member also in the form of a compressible stem or post 26. This stem or post 26 has an enlarged lower portion or annular supporting flange 29 extending outwardly of the stem or post 26. The said lower portion or flange 29 is yieldable and has its undersurface concaved as at 31 to form what is commonly called a suction cup and the annular edge portion 29a of said flange is in tight contact with the flat bottom of the base member, whereby the said compression member 26 and the base bottom portion 17' are operatively and removably associated with one another to absorb pressure of ice formation.

It will be understood that the modification in the construction of the compressible member 26 of Fig. 5 in no way prevents the said compression member including its integral yieldable annular flange 29, from absorbing the expansion caused by the forming of ice in the container 10.

The construction of the fowl drinking fountain illustrated in Fig. 6 is similar to the construction of Fig. 5 with the exception that the base member 11 is made from a material that is not necessarily flexible but may have associated therewith the compressible member of Fig. 5 to protect the container thereof.

It is to be understood that this change of material, in the base member 11 of the fowl drinking fountain, from a flexible to a non-flexible material only necessitates the use of a material for the base member having strength enough to withstand the pressure exerted upon it by the ice formed therein. In no other way does it effect the operation of the present invention.

The invention has been heretofore described in connection with a fowl drinking fountain but it is not limited to this specific use or environment.

The modification of the invention disclosed in Fig. 8 illustrates an open top container or receptacle 36 having a bottom 37 and upstanding walls 38 centrally of which is the compressible member, stem or post 26. The said stem or post 26 is provided at its lower end with a bottom or annular flange 29 which has its undersurface concaved at 31 similar in all respects to the compressible member, stem or post 26, illustrated in Figs. 5 and 6. The container 36 may be formed of any desirable material which would be subject to cracking, distortion or breakage due to pressure caused by the expanding water when turning to ice and upon subsequent further freezing.

The modification of Fig. 7 shows another type

of compression member 32. This compression member 32 is similar to the compression member 26 of Fig. 5, having a lower portion or annular flange 33 concaved on its undersurface to form a suction cup 34. Rising from the suction cup 34 is the stem or post 35 which is solid instead of being centrally cored as illustrated in Figs. 3, 5, 6 and 8.

The solid stem or post 35 of Fig. 7 is made particularly possible since this form is made of a soft or sponge rubber having, as is well understood, considerably more compressibility than the more solid form of rubber. To increase the compressibility of the more solid form of rubber is the reason for providing the hollow or air core in the forms illustrated in Figs. 3, 5, 6 and 8.

It is to be understood that the solid compression member 32 may be inserted in the place of compression member 26 in the constructions of Figs. 5 and 6 and will in no way alter the operation of absorbing the expansion of the water 25 while it is freezing or turning to ice in the fowl drinking fountain.

In view of the foregoing it is now believed evident that there has been provided a fowl drinking fountain containing means for absorbing the expansion of the ice formed therein that overcomes the objections to prior structures and accomplishes the objects initially set forth.

What is claimed is:

1. A poultry drinking fountain of the barometric type, comprising a dish-shaped base having two liquid retaining areas separated by an annular boss extending upwardly from said base and formed with a discharge opening therethrough communicating with the liquid retaining areas of said base, an inverted container having a closed end and an open end in fitting relationship with said boss whereby liquid in said inverted container may flow into the liquid retaining areas of said base, and a post of deformable material extending from said base through the open end of said container in spaced relation to the inner wall surface thereof, said post extending substantially the entire depth of said container whereby said post will absorb pressure of ice formation in said container regardless of the level of liquid therein.

2. A poultry drinking fountain of the barometric type, comprising a dish-shaped base composed of elastic, rubber-like form-retaining ma-

terial, said base having two liquid retaining areas separated by an integral boss extending upwardly from said base and formed with a discharge opening therethrough communicating with the liquid retaining areas of said base, an inverted container having a closed end and an open end in fitting relationship with said boss whereby liquid in said inverted container may flow into the liquid retaining areas of said base, and a deformable hollow post integral with said base and extending from said base through the open end of said container in spaced relation to the inner wall surface thereof, said post extending substantially the entire depth of said container whereby said post will absorb pressure of ice formation in said container regardless of the level of liquid therein.

3. An animal drinking fountain comprising a container having a substantially flat bottom and an annular wall upstanding therefrom, a substantially vertical compression member centrally disposed in said container, said compression member having an annular flange at its lower end and said flange having a concaved lower surface, said flange terminating in an annular edge portion resting on said flat bottom adjacent the junction of said bottom and said wall and forming a water-tight contact with said bottom, whereby pressure of ice formation in said container is absorbed by said compression member and by yielding of said concaved annular flange thereof.
